MULTIPLE ELECTRIC PLUG TAP WITH
MEANS TO SECURE ADDITIONAL TAPS
THERETO

David B. Cohane, Flushing, N. Y.

Application January 31, 1951, Serial No. 208,832

1. Claim. (Cl. 339—76)

This invention relates to plugs for electric cords and the like and in particular a plug having prongs of the conventional type extended therefrom and a threaded collar positioned to coact with the prongs for locking the plug in position upon a wall outlet or the like and in which the plug is also provided with threaded rims positioned around prong receiving sockets for connecting similar plugs thereto.

The purpose of this invention is to provide a three way or multiple outlet plug for connecting a plurality of electric cords to a common outlet whereby cords extended from the plug and also the plug are positively secured in position so that accidental separation of the plugs or of the multiple plug from the wall socket is prevented.

In the conventional type of three way or multiple plug where contact prongs extend from one side and prong receiving openings are provided in other parts thereof, the weight of a cord extended from the plug has a tendency to withdraw the multiple plug from a wall socket and where only prongs are used for connecting cords to the multiple plug the plugs of the cord are accidentally withdrawn or partly withdrawn whereby short circuits are caused and damage often results therefrom. With this thought in mind this invention contemplates a plug which combines the conventional contact prongs with a threaded locking cap whereby the plug is positively secured in a wall receptacle and also a plug that includes the conventional contact prong receiving slots or openings with threaded rims around the openings whereby plugs of a similar type may be positively secured thereon.

The object of this invention is, therefore, to provide a multiple plug which is designed to receive plugs of electric cords in which the plugs of the cords are of the combination type which combine the conventional prongs with threaded locking elements for positively securing the plugs in contacting relation with the multiple plug.

Another object of the invention is to provide a multiple plug that is designed to receive combination contact prongs and screw locking elements of electric cord plugs which is also adapted to receive conventional plugs of electric cords.

A further object of the invention is to provide an improved multiple plug for providing means for attaching a plurality of electric cords to a common wall outlet and wherein both contact prongs and screw locking elements are used for connecting electric cord plugs thereto, which is of a simple and economical construction.

With these and other objects and advantages in

view the invention embodies a plug having a body formed in two sections with a mounting disc having an annular flange thereon positioned on one of the sections, spaced contact prongs extended from the sections of the body and through the mounting disc and an internally threaded collar rotatably mounted on said mounting disc, the said sections of the body having a plurality of sockets including prong receiving slots and threaded rims around the slots positioned on the outer surfaces thereof.

Other features and advantages of the invention will appear from the following description taken in connection with the drawing wherein:

Figure 1 is a longitudinal section through the improved multiple plug being taken on line 1—1 of Fig. 2.

Figure 2 is a section through the plug taken on line 2—2 of Fig. 1.

Figure 3 is a side elevational view of the plug looking toward one of the outlet sockets thereof and showing the plug on a reduced scale.

Figure 4 is a similar view looking toward one side of the plug and illustrating the relative positions of the outlet sockets thereof.

Referring now to the drawing wherein like reference characters denote corresponding parts the improved multiple or three way plug of this invention includes a plug body formed with sections 10 and 11, a mounting disc 12 which is secured to the section 11 by a bolt 13 and a collar 14 that is freely rotatable on the mounting disc 12.

The section 10 of the body is provided with elongated slots 15 and 16 and complementary sections 17 and 18 of the slots are provided in the section 11, as shown in Fig. 3. Connecting slots 19 and 20 extend through the section 11 of the body with the inner ends thereof communicating with the lower sections 17 and 18 of the slots. The section 10 of the body is also provided with slots 21 and 22 through which prongs 23 and 24 extend respectively and, as shown in Fig. 1, the inner ends of the prongs are provided with spring arms 25 and 26 that are positioned to contact prongs inserted in the slots 19 and 20, respectively.

The inner sections 21 and 23 of the prongs 23 and 24 extend outwardly into recesses 29 and 30 in the side walls of the slots of the sections of the plug body, and as illustrated in Fig. 2 the section 21 of the prong 23 is connected to a transversely disposed clip 31 by a rivet 32 and the ends of the clip are provided with spring contact sections 33 and 34 which extend into slot

15. The section 28 of the prong 24 is provided with a similar clip which is indicated by the numeral 35 and the clip 35 is provided with spring contact sections 36 and 37 and these sections extend into the slot 16. The clip 35 is secured to the section 28 of the prong by a rivet 38.

The contact ends 33, 34, 36 and 37 also extend into the complementary sections of the slots 15 and 16 and the ends of the slots extend into counterbores 39 and 40 in opposite sides of the plug body whereby similar contact prongs or prongs of conventional electric plugs may be inserted in the slots to contact the spring contact sections of the clips.

The counterbores 39 and 40 which extend into both sections 10 and 11 of the plug body are surrounded with threaded rims 41 and 42 upon which collars similar to the collar 14 of similar plugs may be threaded.

The slots 19 and 20 also extend into a similar counterbore 43 in the side of the plug opposite to that from which the prongs 23 and 24 extend and the counterbore 43 is provided with a threaded rim 44.

The mounting disc 12 is provided with an annular flange 45 and a similar inwardly extended annular flange 46 on the collar 14 extends over the flange 45 whereby the collar is freely rotatable on the mounting disc. With the prongs 23 and 24 inserted in prong receiving slots or openings in the plug or wall receptacle the collar 14 may be threaded on a rim 47 positioned on the outer surface of a wall plate 48 of a receptacle or outlet box.

With the parts arranged in this manner the improved multiple outlet plug of this invention is inserted in an outlet box or wall receptacle by placing the prongs 23 and 24 in the conventional slots or openings of the receptacle and with the

prongs in position the collar 14 is threaded on a rim or other extension on the base or wall plate of the receptacle, as illustrated in Fig. 1.

It will be understood that modifications may be made in the design and arrangement of the parts without departing from the spirit of the invention.

What is claimed is:

A plug having multiple faces for electric fixture cords formed of two similarly shaped sections, a mounting disc having an enlarged annular flange in engagement with one face of said plug, an externally threaded rim surrounding the outer faces of the said plug, a bolt extending through said sections and mounting disc to retain the same in fixed relation to each other, a collar having an externally threaded portion and an internal flange, the collar being mounted on the mounting disc so that the flange of the collar will engage the flange of the disc whereby the collar is rotationally mounted on said mounting disc, prongs extending outwardly of the plug within the collar mounted on said disc, prong receiving sockets in the other faces of said plug, electric contacts in said plug and positioned to engage prongs inserted in said sockets and the said collar adapted to be mounted on the threaded external rim of a similarly formed plug to retain the two plugs in fixed relation to each other.

DAVID B. COHANE.
